CARTON CARRYING AND CUTTING IMPLEMENT

John H. Schuster, Simla, Colo.

Application August 27, 1956, Serial No. 606,339

5 Claims. (Cl. 7—14.1)

This invention relates to a novel implement which may be readily inserted into a carton to bear against undersides of top flaps of the carton and which is provided with a handle which is upwardly offset relative to the top flaps and which can be conveniently grasped for carrying a sealed carton and its contents.

Another object of the invention is to provide an implement of the aforescribed character a part of which additionally forms a blade which is adapted to be utilized for cutting the top flaps or for breaking the seal between top flaps of the carton to enable the carton to be readily opened.

Still a further object of the invention is to provide an implement which due to its unique construction can be readily inserted under top flaps of a carton without breaking the seal connecting the top flaps and so that the filled carton can be readily carried by the implement which supports the carton and its contents solely by contact with the sealed top flaps of the carton.

A further object of the invention is to provide such a carrying implement wherein the implement handle can be conveniently positioned centrally above the sealed carton and crosswise thereof so that the carton will be balanced beneath the implement when carried thereby, to enable carrying of the carton with the least manual effort.

A further object of the invention is to provide an implement by means of which a carton, normally requiring the use of both hands for carrying, may be carried with one hand utilizing the implement, so that two cartons may be conveniently carried simultaneously by a person employing two of the implements.

Various other objects and advantages of the invention will hereinafter become more fully apparent from the following description of the drawing, illustrating a presently preferred embodiment thereof, and wherein:

Figure 1 is a top plan view of a conventional sealed carton and showing the implement in top plan being applied thereto;

Figure 2 is a fragmentary top plan view showing the implement in a fully applied position for carrying the carton, and on an enlarged scale;

Figure 3 is a fragmentary vertical sectional view taken substantially along a plane as indicated by the line 3—3 of Figure 2;

Figure 4 is a perspective view of one of the two halves of the implement, and

Figure 5 is an enlarged fragmentary longitudinal sectional view of the implement, taken substantially along a plane as indicated by the line 5—5 of Figure 2.

Referring more specifically to the drawing, the carton carrying and cutting implement in its entirety and comprising the invention is designated generally 7 and consists of two substantially identical members, designated generally 8 and 9. Accordingly, a description of one will suffice for both.

Each of the implement halves or members 8 and 9 is

2

formed from an elongated strip of steel and includes a substantially flat end portion forming a blade 10, an opposite end portion forming a handle, designated generally 11, and an intermediate portion forming a shank 14 which extends between and connects adjacent ends of the blade and handle. The blade 10 has beveled side edges and a beveled outer end to provide a continuous cutting edge 12. The outer end of the blade 10, as defined by a portion of the cutting edge 12, is preferably rounded as seen at 13.

The end of the strip forming the handle 11 is folded longitudinally along two transversely spaced substantially parallel lines, so that the handle 11 is of channel shape in cross section and includes a bottom 15 and spaced substantially parallel upstanding walls 16.

The shank 14 is substantially flat and is disposed at approximately a right angle to the planes of the blade 10 and handle 11 and has a lower end merging integrally with the inner end of the blade 10 and an upper end merging integrally with an inner end of the handle 11. Thus, the handle 11 is upwardly offset with respect to the blade 10, as clearly illustrated in the drawing. The member 8 or 9 is also provided with a transversely extending slot 17 which opens outwardly of one longitudinal edge thereof and which is formed in a part of the bend 18 where the inner end of the blade 10 joins with the lower end of the shank 14 and is of a length slightly greater than one-half the width of the blade 10 and shank 14.

The member 8 has an opening 19 formed in the blade 10 adjacent the rounded end 13 thereof and the member 9 has an opening 20 formed in the blade 10 thereof and which is spaced a greater distance from its rounded end 13 than the spacing between the rounded end 13 and the opening 19 of the member 8. This difference in spacing of the openings 19 and 20 from the outer ends 13 of the blades 10 constitutes the sole difference between the implement halves or members 8 and 9.

A conventional carton 21 is illustrated in Figure 1 having side flaps 22 which extend from end-to-end thereof, end portions of which overlie and are sealed to end flaps 23 of the carton. The side flaps 22 are shown with their adjacent edges spaced slightly apart to form a slot 24 therebetween which is open between the end flaps 23, as is conventional in connection with many cartons. The blades 10 are inserted through the open intermediate portion of the slot 24 in opposite directions, as illustrated in Figure 1, so that the blade 10 of the member 8 is positioned under the intermediate portion of one flap 22 and the blade 10 of the member 9 is positioned under the intermediate portion of the other flap 22. The blades 10 are inserted so that the slots 17 of the members of which said blades form parts will open toward one another, and one of the members is then manipulated by its handle 11 to position the slots 17 in interengaging relation with one another and with the bends 18 which are disposed beyond the inner ends of the slots 17, so that the shanks 14 will be disposed in abutting engagement with one another and so that the blades 10 will be disposed coplanar and in alignment to thus position the handles 11 in alignment and coplanar, as illustrated in Figures 2 and 3. With the implement halves thus connected together and with the blades 10 thereof positioned beneath the flaps 22 and crosswise thereof, the two aligned handles 11 can be grasped with either hand and with two of the fingers straddling the abutting shanks 14 for lifting and carrying the carton 21 and its contents by the implement 7.

It will also be apparent that either half 8 or 9 of the implement 7 may be utilized, when disconnected from the other implement half, for opening the carton 21, by

the user grasping the handle 11, of the implement half which is employed, and utilizing the blade 10 as a knife for cutting the sealing connection between the flaps 22 and 23 with the cutting edge 12. The cutting edge 12 of the blade 10 can also be employed for cutting off the flaps 22 and 23, if desired. It will also be apparent that the sharpened rounded ends 13 of the blades 10 may be utilized for penetration of the blades between the flaps 22 where no slot, such as the slot 24, exists, and for providing an opening between the adjacent edges of the flaps 22 when sealed together, so that the two implement halves can be manipulated for arranging them in interconnected relation with one another as seen in Figures 2, 3 and 5, for use of the implement halves as a carrying unit.

The openings 19 and 20 are adapted to be utilized for engaging a hook or nail by which the implement halves 8 and 9 may be hung for storage when not in use. The opening 20 is spaced a greater distance from the blade end than the opening 19 so that the blade 10 of the member 9 will be disposed to overlie the blade 10 of the member 8, when both openings 19 and 20 are engaging a nail or hook, not shown, and in order to offset the members 8 and 9 relative to one another in a direction lengthwise thereof so that said members 8 and 9 can be conveniently stored in overlying relation.

Various modifications and changes are contemplated and may be resorted to without departing from the function or scope of the invention as hereinafter defined by the appended claims.

I claim as my invention:

1. An implement formed of corresponding halves each formed from an elongated substantially rigid strip having an elongated substantially flat first end portion forming a blade and an elongated second end portion forming a handle, said implement halves each including an intermediate portion forming a shank, said shank being disposed in a lateral position relative to the blade and handle for offsetting the handle relative to the blade, said implement halves each having a slot disposed crosswise thereof and opening outwardly of a side edge of the implement half at the junction of the shank and blade and extending part way across the shank and blade, said slots interfitting with one another for positioning said shanks in substantial abutting engagement and to position the

blades of the two implement halves in alignment and substantially coplanar with one another and for positioning the handles substantially in alignment and coplanar to one another, said blades being adapted to engage the undersides of top flaps of a sealed carton, said shanks being adapted to extend outwardly from the blades between the carton flaps for positioning the handles above and spaced from the carton.

5 2. An implement as in claim 1, at least one of said blades having sharpened longitudinal side edges and a sharpened outer end disposed remote from the shank whereby said implement half is adapted to be utilized for cutting and effecting penetration of the carton.

10 3. An implement as in claim 1, the strip end of each implement half forming the handle thereof being bent along two transversely spaced lines to form the handle of channel shaped cross section including a bottom portion disposed substantially parallel to the blade and laterally spaced upstanding side walls rising from the handle bottom.

15 4. An implement as in claim 1, said blades having openings spaced different distances from the ends thereof and adapted to be disposed in alignment when the blades and handles of the implement halves are positioned in overlying relation.

20 5. An implement comprising implement halves each including an elongated substantially flat blade, an elongated handle and a shank, the shank of each implement half being disposed at substantially a right angle to the blade and handle thereof for offsetting the handle relative to the blade, said blade and handle extending in opposite directions from the ends of the shank, and means for interconnecting said implement halves with one another for positioning the blades thereof substantially in alignment and coplanar with one another and for positioning the handles substantially in alignment and coplanar with one another, said blades being adapted to engage the inner sides of carton flaps, and said shanks being adapted to extend outwardly from the blades between the carton flaps for positioning the handles above and spaced from the carton.
